WAVE GENERATOR

Gerhard E. Weibel, Manhasset, N.Y., assignor, by mesne assignments, to Sylvania Electric Products Inc., Wilmington, Del., a corporation of Delaware

Application September 26, 1958, Serial No. 763,690

8 Claims. (Cl. 313—162)

My invention is directed toward wave generators.

In the electronic art it has become necessary to provide devices for generating electromagnetic waves having wavelengths shorter than a centimeter; i.e. millimeter and submillimeter waves. I have invented a device (defined herein as a wave generator) which can be used for this purpose.

Accordingly, it is an object of my invention to generate millimeter and submillimeter waves.

Another object is to provide new methods for generating electromagnetic waves.

Yet another object is to provide new types of devices for generating electromagnetic waves.

Still another object is to provide new millimeter and submillimeter wave generators for producing millimeter and submillimeter waves at high power levels.

Yet a further object is to accelerate electrons in such manner that the accelerated electrons radiate energy in the form of submillimeter waves.

In accordance with the principles of my invention, I provide an evacuated, cylindrical, hollow radiation chamber. A substantially homogeneous unidirectional magnetic field having a first field flux density B_0 is established within the chamber, the magnetic field vector pointing in a direction parallel to the axis of the chamber. A portion of an electron beam is introduced into the chamber, the axis of the beam being coincident with the axis of the chamber. This beam portion is radially and axially confined and constitutes a cylindrical element, the diameter of which is of the order of the wavelength to be generated. Stated differently, the cylindrical element constitutes an elongated element of relatively short length and very small cross section; I define such an element as an electron pencil. The pencil rotates about its own axis, the axis of the pencil being coincident with the axis of the chamber.

An alternating electric field of frequency f_0 is established within the chamber, the electric field vector always pointing perpendicular to the magnetic field vector. The frequency of the electric field is so related to the first magnetic field flux density B_0 that the pencil, while continuing to rotate about its own axis, spirals radially outward from the axis of the chamber with a continually increasing radius.

The magnetic field flux density is then increased to a second and much higher value B_{max} . As a result, the pencil, while continuing to rotate about its own axis, spirals radially inward toward the axis of the chamber with a continually decreasing radius. The pencil is so accelerated during this inward spiralling process that it emits very high frequency radiation having a maximum frequency f_{max} proportional to the second magnetic field flux density B_{max} . During the interval in which the magnetic field increases, the power level of this radiation is proportional to the third power of the magnetic field intensity at the instant when the radiation is emitted.

More particularly, the radiation chamber comprises two separated semicircular sections which together define

2

a cylinder. A first planar electrode, termed the repeller electrode, is positioned adjacent one end of the cylinder. A second planar electrode, termed the gate electrode, is positioned adjacent the other end of the cylinder. The gate electrode is provided with an orifice, the center of which is coincident with the axis of the cylinder. The gate electrode is maintained at a first negative potential with respect to both cylindrical sections; the repeller electrode is maintained at a second and more negative potential with respect to both cylindrical sections.

A homogeneous unidirectional magnetic field having a first magnetic field flux density B_0 is established within the chamber, the magnetic field vector pointing in a direction parallel to the axis of the cylinder.

An electron beam is directed from an electron gun (the cathode of which is maintained at fixed potential approximately equal to that on the gate electrode) through the orifice of the gate electrode into the chamber, the axis of the beam being coincident with the axis of the cylinder. As will be explained in more detail hereinafter, the electrons in the beam rotate or spin about the beam axis. The negative potential on the repeller electrode repels the electrons therefrom. The repelled electrons then escape thereafter from the chamber through the gate orifice, thus establishing what I define as a "double streaming" condition for the electron beam.

The potential difference between the cylindrical sections on the one hand and the cathode, repeller and gate electrodes on the other hand is then increased, while the potential difference between the cathode and the electrodes is held constant. As the potential difference between the sections and the electrodes is increased, an increasing number of electrons with low thermal initial velocity in the double streaming beam become trapped within the chamber (while spinning about the cylindrical axis). The magnetic field radially confines the trapped electrons into an electron pencil which rotates about its own axis, the pencil axis being coincident with the axis of the cylinder.

An alternating electric field of frequency f_0 is then applied between the two cylindrical sections, the electric field vector necessarily pointing in directions always perpendicular to the magnetic field vector. The frequency f_0 of the electric field is chosen to be equal to the quantity e/mB_0 , where e is the charge of the electron and m is the electron mass. Under these conditions, the combined interaction of the electric and magnetic fields upon the pencil is such that the pencil, while continuing to rotate about its own axis, spirals outward from the axis of the cylinder with a continually increasing radius.

The magnetic field intensity is then increased; the radial dimension of the pencil shrinks and further the pencil spins inward toward the axis of the cylinder with a continually decreasing radius. The acceleration of the electron pencil during the last portion of this inward spiralling action is extremely high, and consequently, electromagnetic waves of very high frequency are generated, the resulting radiation passing out of the radiation chamber through suitable slots in the two cylindrical sections.

When the magnetic field flux density is increased to a maximum value of B_{max} , the frequency of f_{max} of the generated waves is equal to e/mB_{max} . Consequently, the frequency f_{max} is equal to the quantity $(B_{max}/B_0)f_0$. In other words, the frequency f_{max} of the generated waves is equal to the product of the frequency f_0 of the applied alternating field and the ratio of the final magnetic field intensity B_{max} to the initial magnetic field flux density B_0 . Further, the ratio of the total available energy for radiation w of the generated wave to the total stored energy W_0 supplied by the applied alternating field is substantially proportional to the ratio of the

frequency $f_{\max}$ to the frequency f_0 . Stated differently, the total available energy W of the generated wave is substantially proportional to the quantity $(f_{\max}/f_0)W_0$.

An illustrative embodiment of my invention will now be described with reference to the accompanying drawings wherein:

Fig. 1 illustrates one embodiment of my invention;

Figs. 2 and 3 are enlarged views of the radiation chamber and the electron beam contained therein as employed in the embodiment of Fig. 1; and

Fig. 4 is a graph of the functional relationship between the radiated power ratios and the magnetic field ratios as utilized in the embodiment of Fig. 1.

Referring now to Fig. 1, there is provided a radiation chamber comprising a disc shaped gate electrode 16 with a central orifice, first and second axially aligned cylindrical sections 20 and 22, and a repeller electrode 18. The axis of the sections passes through the center of the gate electrode orifice in a direction perpendicular to the surface of the gate electrode 16. Each of sections 20 and 22 is constituted by two semicircular halves, one set of corresponding halves of sections 20 and 22 being grounded, the other set being coupled through capacitor 26 to one of terminals 24.

An electron beam 46 produced by electron gun 10 is directed through accelerating electrode 12, focussing electrode 14 and the orifice of gate electrode 16 into the radiation chamber. A magnetic field having a flux density of B_0 is established within the chamber, the magnetic field vector pointing in a direction parallel to the axis of the chamber.

Initially, no voltages are applied across either of terminal pairs 28 and 24. Under these conditions, batteries 32 and 34 and 36 and 38 establish a potential profile 100 for the system. More particularly, the cylindrical sections 20 and 22 are at ground potential; gate and repeller electrodes are at first and second negative potentials, the first potential being slightly more positive than the second potential; the focussing electrode is maintained at the same potential as the gate electrode, namely, the first negative potential; the accelerating electrode is maintained at a third negative potential somewhat more positive than either of the first and second potentials; and the gun 10 is maintained at a fourth potential slightly more negative than the first potential.

The electron beam travels through the orifice of the gate electrode 16 along the axis of the chamber to the repeller electrode 18. The electrons in the beam are reflected from the repeller electrode (due to its negative potential). These reflected electrons escape backward through the orifice of the gate electrode. Consequently, a "double streaming" condition is established for the beam, since some electrons are entering the chamber and other electrons are leaving the chamber. Moreover, because of action of the magnetic field (which also prevents the beam from dispersing), the electron beam rotates continuously about its axis (which is coincident with the axis of the chamber).

It will be apparent from Fig. 1, curve 100, that a potential "well" is established within the chamber. A control voltage, in the form of a negatively increasing trapezoidal shaped pulse, is applied between terminals 28. As a consequence, the potential well becomes deeper as a function of time (see curves 102 and 104 in Fig. 1) and electrons are trapped within the chamber.

The trapping action can be explained in the following manner. An electron enters the chamber through the gate at low velocity and is accelerated toward the center of the chamber with a force closely proportional to the distance from it. As long as all potentials are kept constant, the electron behaves as a linear oscillator moving back and forth in the chamber once, then escaping through the gate with the same velocity it had when entering. On the other hand, when the gate and repeller potentials are negatively increasing, the restor-

ing force of the electron-oscillator increases with time, resulting in a decreasing amplitude of excursion from the center. If the restoring force increases sufficiently fast, an electron will be unable to reach the gate after completing one round trip in the chamber; it will be thrown back toward the center and become trapped and continue to oscillate.

The electrons are injected through the gate at rather low velocity, and have substantially a Maxwell-Boltzmann velocity distribution determined by the temperature of the cathode. The trapping condition will be fulfilled only for a low thermal velocity fraction of the electrons; the fast ones will escape. While the beam is continuously injected in the gun, the gate and repeller electrodes are pulsed negative; the result is a continuous accumulation of space charge in the chamber. When a sufficient number of electrons have been thus trapped, the beam is cut off and the gate and repeller electrodes are maintained at constant, high negative potentials with respect to the shield. Electrons that were injected at the beginning of the trapping phase oscillate with very small amplitudes around the center of the chamber, while those that entered later have progressively larger amplitudes; the electrons injected just before the stream was shut off travel through the beam over its whole length. The rate at which electrons pass through any arbitrary plane perpendicular to the beam is the same in both directions.

The trapped electrons then constitute an electron pencil rotating about the axis of the chamber, the diameter of the pencil being maintained at a desired fixed value determined by the value of B_0 . Since individual electrons in the pencil oscillate back and forth between the gate and repeller electrodes, the electron pencil forms a segment of a double streaming beam.

An alternating voltage of frequency f_0 is then applied between terminals 24. As previously indicated, this frequency is equal to the quantity e/mB_0 . This relationship, as is known to the art, is that required for cyclotron resonance. Consequently, the entire electron pencil, while continuing to rotate about its own axis, revolves about the axis of the chamber in a continuously larger orbit; i.e. the pencil spirals outward from the axis of the chamber with a continually increasing radius as is shown in Fig. 2.

More particularly, under the influence of the transverse electric field at cyclotron frequency, the beam maintains its shape and diameter, moving with its axis along the same spiral a single electron originating from the rest position of the beam axis. At the same time, the beam continues to rotate around its axis with an angular velocity equal to one half of that associated with its spiraling motion. The beam possesses angular momentum, part of which is due to rotation about its own axis ("spin angular momentum") and part due to the spiraling motion of the beam axis ("orbital angular momentum"). During this phase of the operation, the spin momentum stays constant, while the orbital momentum increases with time.

As the beam spirals outwards, it subtends a progressively smaller angle from the axis of the chamber. Phase focusing of the electrons is therefore produced, resulting in a convection current density that is periodic in time with the cyclotron frequency and in phase at all points in a meridian half plane.

As soon as the beam is spiralled outward to a sufficiently large orbital radius, an ultra-high magnetic field is pulsed in the direction of the focusing field; this pulse can be, for example, a trapezoidal shaped pulse having a rise time, for example, of 10^{-7} – 10^{-6} seconds. During the rise time of the magnetic pulse, the parameters describing the motion are changing in the following manner: The angular velocity ω of the orbital motion increases proportionally with the magnetic flux density B , the radius r of the orbit decreases with $B^{-1/2}$ and the beam diameter

shrinks proportionally with B^{-1} . Since the energy W stored in the orbital motion is proportional to $\omega^2 r^2$, this means that W increases proportionally with B or ω .

As the magnetic field intensity increases, the diameter of the pencil shrinks and further, the pencil spins inwardly toward the axis of the chamber while continuing to rotate about its own axis as shown in Fig. 3. At the end of the pulsing process, the pencil is subject to extremely high acceleration during this inward spiralling process, and generates electromagnetic waves of very high frequency. The resultant radiation is circularly polarized and is emitted from the chamber through the narrow ring shaped region between sections 20 and 22. (Note that an electron when accelerated will always emit radiation, but this radiation only becomes appreciable for high values of acceleration.)

The frequency f of the radiation at any instant is equal to the product of the initial frequency f_0 and the ratio of the magnetic field intensity B at this instant to the initial magnetic field intensity B_0 ; i.e.

$$f = f_0 (B/B_0)$$

Further, the available energy W of the radiation at the end of the magnetic pulsing period is equal to the product of the energy W_0 supplied by the alternating electric field to the electron pencil and the ratio f/f_0 ; i.e.

$$W = W_0 (f/f_0)$$

However, the rate at which energy is radiated, i.e. the radiated power P , is proportional not to the first power of the ratio B/B_0 , but rather is proportional to the third power of this ratio, i.e. $(B/B_0)^3$. Hence, as the magnetic field intensity increases, the amount of radiated power increases very rapidly. If the magnetic field intensity is increased to a maximum value $B_{\max}$, and the radiated power corresponding to this value is $P_{\max}$, then power P radiated for any intermediate value of the magnetic field intensity B can be computed from the curve of Fig. 4 through use of two ratios $P/P_{\max}$ and $B/B_{\max}$.

At the end of the magnetic field pulsing period, the electron gun is again energized and the entire procedure is repeated, thus providing means for periodically generating electromagnetic waves of high frequency.

The values of the tube parameters such as dimensions, voltage and magnetic field flux densities and the like, depend, of course, upon the desired operating conditions. As an example, illustrative design values for generating millimeter waves are given below.

The chamber dimensions—6 millimeters in length and 8.2 millimeters in diameter; B_0 —1000 gauss; $B_{\max}$ —100,000 gauss; alternating electric field—wavelength of 11 centimeters at a power level of 0.16 watt for a period of 100 microseconds; emitted radiation—minimum wavelength of 1.1 millimeter at a power level of 160 watts for a period of 1 microsecond; the electron pencil—6 millimeters in length and 0.02 millimeter in diameter containing 10^9 electrons. Under these conditions, the control voltage pulse will have a maximum value of 4000 volts with respect to ground.

What is claimed is:

1. A wave generator comprising an evacuated cylindrical radiation chamber; means to establish a magnetic field having a first flux density B_1 within said chamber, the magnetic field vector pointing in a direction coincident with the axis of said chamber; means to introduce an electron pencil into said chamber, the pencil axis being coincident with the axis of the chamber, said pencil rotating about its axis; means to establish an alternating electric field of frequency f_1 within said chamber, the electric field vector being perpendicular to the magnetic field vector, the frequency of said electric field being so related to the first magnetic flux density that the pencil undergoes cyclotron resonance and spirals outward from the axis of the chamber while continuing to spin about its axis; and means to increase the magnetic field flux

density to a second value B_2 whereby said pencil spins inward toward the axis of the chamber with a continually decreasing radius and emits radiation, the frequency f_2 of said radiation being equal to the product $(B_2/B_1)(f_1)$.

2. A wave generator comprising an evacuated cylindrical radiation chamber; means to establish a magnetic field having a first flux density within said chamber, the magnetic field vector pointing in a direction coincident with the axis of said chamber; means to introduce electrons into said chamber; means to trap and confine said electrons within said chamber in the form of an electron pencil, the pencil axis being coincident with the axis of the chamber, said pencil rotating about its axis; means to establish an alternating electric field having a first frequency within said chamber, the electric field vector being perpendicular to the magnetic field vector, the frequency of said electric field being so related to the first magnetic flux density that the pencil undergoes cyclotron resonance and spirals outward from the axis of the chamber while continuing to spin about its axis; and means to increase the magnetic field flux density to a second value whereby said pencil spins inward toward the axis of the chamber with a continually decreasing radius and emits radiation, the ratio of frequency of said radiation to that of said alternating field being equal to the ratio of said second flux density to that of said first flux density.

3. A wave generator comprising an evacuated cylindrical radiation chamber including a hollow slotted cylindrical section open at both ends, a repeller electrode positioned adjacent one end of said section, and an apertured gate electrode positioned adjacent the other of said section, the surfaces of both electrodes being perpendicular to the axis of said section; means to establish a magnetic field having a first flux density within said chamber, the magnetic field vector pointing in a direction coincident with the axis of said chamber; means to direct an electron beam into said chamber through the aperture of said gate electrode; means to trap a portion of said beam in said chamber in the form of an electron pencil, the axis of said pencil being coincident with the axis of said section, said pencil rotating about its axis; an alternating electric field having a first frequency within said chamber, the electric field vector being perpendicular to the magnetic field vector, the frequency of said electric field being so related to the first magnetic flux density that the pencil undergoes cyclotron resonance and spirals outward from the axis of the chamber while continuing to spin about its axis; and means to increase the magnetic field flux density to a second value whereby said pencil spins inward toward the axis of the chamber with a continually decreasing radius and emits radiation, the ratio of frequency of said radiation to that of said alternating field being equal to the ratio of said second flux density to that of said first flux density.

4. A wave generator comprising an evacuated cylindrical radiation chamber including a hollow slotted cylindrical section open at both ends, a repeller electrode positioned adjacent one end of said section, and an apertured gate electrode positioned adjacent the other end of said section, the surfaces of both electrodes being perpendicular to the axis of said section, said section being maintained at a first potential, said gate and repeller electrodes being maintained at second and third potentials respectively, said first potential being more positive than either of said second and third potentials, said third potential being negative with respect to said second potential; means to establish a magnetic field having a first flux density within said chamber, the magnetic field vector pointing in a direction coincident with the axis of said chamber; means to direct an electron beam into said chamber through the aperture of said gate electrode whereby the electrons approach said repeller electrode and are then repelled backward through said chamber thus establishing a double streaming condition for said beam; means to negatively increase said second and third

potentials to trap a portion of said beam in said chamber in the form of an electron pencil, the axis of said pencil being coincident with the axis of said section, said pencil rotating about its axis; means coupled to said section to establish an alternating electric field having a first frequency within said chamber, the electric field vector being perpendicular to the magnetic field vector, the frequency of said electric field being so related to the first magnetic flux density that the pencil undergoes cyclotron resonance and spirals outward from the axis of the chamber while continuing to spin about its axis; and means to increase the magnetic field flux density to a second value whereby said pencil spins inward toward the axis of the chamber with a continually decreasing radius and emits radiation, the ratio of frequency of said radiation to that of said alternating field being equal to the ratio of said second flux density to that of said first flux density.

5. A method for generating electromagnetic waves in an evacuated cylindrical radiation chamber comprising the steps of establishing a magnetic field having a first flux density within said chamber, the magnetic field vector pointing in a direction coincident with the axis of said chamber; injecting electrons into said chamber; trapping and confining said electrons within said chamber in the form of an electron pencil, the pencil axis being coincident with the axis of the chamber, said pencil rotating about its axis; establishing an alternating electric field having a first frequency within said chamber, the electric field vector being perpendicular to the magnetic field vector, the frequency of said electric field being so related to the first magnetic flux density that the pencil undergoes cyclotron resonance and spirals outward from the axis of the chamber while continuing to spin about its axis, and increasing the magnetic field flux density to a second value whereby said pencil spins inward toward the axis of the chamber with a continually decreasing radius and emits radiation, the ratio of frequency of said radiation to that of said alternating field being equal to the ratio of said second flux density to that of said first flux density.

6. A wave generator comprising an evacuated cylindrical radiation chamber; means to establish a magnetic field having a first flux density within said chamber, the

7 magnetic field vector pointing in a direction coincident with the axis of said chamber; means to introduce electrons in the form of an electron beam into said chamber along one direction coincident with the axis of said chamber, said electrons thereafter leaving said chamber in an opposite direction thereby establishing a double streaming condition for said beam; means to trap and confine a portion of said electrons within said chamber in the form of an electron pencil, the pencil axis being coincident with the axis of the chamber, said pencil rotating about its axis; means to establish an alternating electric field having a first frequency within said chamber, the electric field vector being perpendicular to the magnetic field vector, the frequency of said electric field being so related to the first magnetic flux density that the pencil undergoes cyclotron resonance and spirals outward from the axis of the chamber while continuing to spin about its axis; and means to increase the magnetic field flux density to a second value whereby said pencil spins inward toward the axis of the chamber with a continually decreasing radius and emits radiation, the ratio of frequency of said radiation to that of said alternating field being equal to the ratio of said second flux density to that of said first flux density.

20 25 7. A wave generator as defined in claim 3 wherein said cylindrical section comprises two adjacent but separated semicircular subsections, said means to establish an alternating electric field being coupled to both subsections.

30 35 8. A wave generator as defined in claim 3 wherein the slots in said cylindrical section extend peripherally and circularly about said section and said radiation is circularly polarized and is emitted radially outward from said section.
